UNITED STATES PATENT OFFICE

2,024,188

MACHINE FOR EQUIPPING WIRED BOX
PARTS WITH FASTENING MEANS

Alfred L. Rosenmund, Rockaway, and George P. Igleheart, Boonton, N. J., assignors to Stapling Machines Co., a corporation of Delaware

Application July 13, 1934, Serial No. 734,906

27 Claims. (Cl. 140—93)

This invention relates to machines for equipping wired box parts with interengageable fasteners and particularly to machines for manipulating a wire secured to a box part to provide 5 the wire end with a bight and to perpetuate that bight by driving the end of the wire into the box part.

It is an object of the invention to provide certain improvements in the machine shown and 10 described in U. S. patent to A. L. Rosenmund No. 1,933,031 of October 31, 1933.

It is a further object to provide a machine of the type shown in said Rosenmund patent with improved means for locating and driving the 15 end of the wire into the box parts.

One illustrative embodiment of the invention is shown in the accompanying drawings in which:—

Figure 1 is a side elevation of a machine embodying the invention.

Fig. 2 is a front elevation of the same.

Fig. 3 is a diagrammatic view of the wire-manipulating elements of the machine shown in stop position with a pair of wire-connected 25 box parts positioned on the supporting table to be operated upon. The dotted lines indicate the table in raised position and the full lines indicate the table in lowered position.

Fig. 4 is a similar view at a different stage in 30 the cycle of operation and showing the position of the different wire-manipulating elements at the time of the prong-forming operation which occurs just after the wire-cutting operation.

Fig. 5 is a similar view showing the position 35 of the wire-manipulating elements after the wire connecting the two box parts has been severed and prongs formed on the ends of the severed wires and after the prongs have been swung over onto their respective box parts to form bights.

Fig. 6 is a similar view showing the position 40 of the parts after the prongs have been driven through the box parts and clinched to perpetuate the bights.

Fig. 7 is a diagrammatic top plan view of two 45 wire-connected box parts illustrating in full lines, the wire prior to a cutting and prong-forming operation, and, in dotted lines, the manner in which the severed ends are swung over onto the box parts to form the bights.

Fig. 8 is a diagrammatic side elevation of two 50 box parts after the wire has been severed and prongs formed on the severed ends and showing the bight-forming spindles in engagement with

the wires and ready to swing the prongs over onto the box parts to form the bights.

Fig. 9 is a perspective top plan view of a wire-bound box blank equipped with interengageable fasteners by the machine of this application. 5

Fig. 10 is a perspective view of a completed box equipped with interengageable fasteners by the machine of this application showing one of the fasteners in an intermediate stage of interengagement and the other fasteners completely 10 interengaged.

Fig. 11 is a perspective view of one of the locator-driver units of the machine showing the position of the parts just prior to locating the 15 end of the wire for a driving operation. 16

Fig. 12 is a side elevation of the same seen from the right in Fig. 11.

Fig. 13 is a sectional view taken on the line 13—13 of Fig. 12.

Fig. 14 is a similar view but showing the position of the parts after the movable locator has 20 positioned the wire end for a driving operation.

Fig. 15 is a similar view showing the position of the parts upon completion of a driving operation. 25

Fig. 16 is a side elevation of the locator-driver unit upon completion of a driving operation with certain parts broken away for clearness of illustration.

Figs. 17 to 22 inclusive are diagrammatic perspective views illustrating the positions of the 30 locator-driver unit during different phases of its cycle of operation.

One illustrative product of the machine of this application is shown in Figs. 9 and 10. Fig. 9 35 discloses a wire-bound box blank consisting of a plurality of sections of cleats A and side sheets B connected together by binding wires C stapled to the several sections. Such wirebound box blanks are made on a box blank machine which 40 staples the wires to the several sections. As successive box blanks emerge from the box blank machine they are connected by the binding wires C, appropriate spaces being left between successive box blanks to permit severing the 45 wires and manipulating the severed ends to provide bights D (see Fig. 9) which bights may be interengaged to close the box, as shown in Fig. 10.

As the wire-connected box blanks emerge from 50 the box blank machine they are fed into the machine of this application and positioned on a vertically movable support or table T, as shown diagrammatically in Fig. 3. As there shown, in the dotted lines, the wire to be operated upon is 55

located directly above the cutters 1, prong-forming blocks 2, and bight-forming spindles 3, and below cutter-actuator 4 carrying prong-forming elements 5; and also below locator-driver units 6 hereinafter described in detail.

In Fig. 3 the parts are at rest preparatory to the start of the machine. The machine is operated through a one-cycle clutch as explained in said patent to Rosenmund No. 1,933,031, and during one cycle of operation the several wire-manipulating elements go through the successive operations shown diagrammatically in Figs. 3 to 7.

As shown in Fig. 3 in the full lines, the table support first lowers the wire C between cutter members 1 and into contact with prong-forming blocks 2. In Fig. 4, the cutter actuator 4 carrying prong-forming elements 5 descends operating the cutters 1 to sever the wire C and bend the severed ends over prong-forming blocks 2 to form prongs P on the ends of the wire. After descent of the cutter-actuator the spindles 3 rise and engage the wire ends. When the cutter-actuator rises, the spindles 3 are partially rotated to swing the prongs over onto the box parts, as shown in Fig. 5. The drivers thereupon descend and drive the prongs into the box parts to perpetuate the bights (see Fig. 6).

The several wire-manipulating elements and the mechanisms for operating the same are disclosed and described in detail in said patent to Rosenmund No. 1,933,031, reference to which is hereby made for a detailed description.

The present invention is directed to an improvement in the driver units which drive the prongs into the box parts to perpetuate the bights, and particularly to the mechanism for locating the prong in correct position beneath the driver and for maintaining it in such position during the driving operation.

In the machine of said Rosenmund Patent No. 1,933,031 the mechanism for locating the prong for a driving operation consists of a pair of arms fixed in spaced relationship to receive between them the prong to be driven, which arms are mounted independently of the driver unit and adapted to be rocked into locating position beneath the driver just prior to the descent of the driver. Such a locator mechanism while generally satisfactory under normal conditions occasionally fails to properly engage and position the prong between the two fixed arms of the locator device. Moreover, the locator mechanism of the said Rosenmund patent being mounted and operated independently of the driver unit requires a separate and somewhat complicated operating mechanism to operate the locator in correlation with the operation of the driver unit.

The present invention is intended to eliminate the objections referred to above and to provide a locator mechanism which is mounted on and becomes a part of the driver unit and which consists of relatively movable locator arms adapted to engage and position the prongs regardless of wide variations in the position of the prong as a result of the bight-forming operation.

Referring to Fig. 11, the locator and driver unit is carried on a cross bar 7 which is reciprocated vertically in the manner described in said Rosenmund patent. The locating and driving elements are supported by a body casting 8 secured to the cross bar 7 by a front plate 9 and bolts 10.

Referring now to Fig. 13, there is secured to the lower end of body casting 8 by rivets 11 a

casting 12 which carries a driver 13 secured to the casting 12 by bolts 14. At either side of the casting 12 are located side plates 15 which are yieldingly held in contact with the casting 12 by bolts 14 and 16 and spring 17.

Mounted to slide vertically in the casting 12 is the locator consisting of a body portion 18, a fixed locator arm 18A and a relatively movable locator arm 18B. Movable locator arm 18B is pivotally mounted on the body portion 18 by a pin 19. Movable locator arm 18B is normally held in its open position at substantially right angles to the fixed locator arm 18A, as shown in Fig. 13, by the action of a spring 20, one end of which is fastened in the body portion 18 and the other end of which is fastened in the movable locator arm 18B.

Secured to the upper end of the body portion 18 is a rod 21 which extends upwardly through casting 12 and into body casting 8, said castings being suitably bored to receive the rod 21.

Referring to Fig. 16, the upper end of the rod 21 is provided with a lug 22 adapted when the rod 21 is in raised position to be engaged and held in raised position by a latch 23 pivotally mounted at the upper end of body casting 8. Latch 23 is yieldingly held in engagement with lug 22 through the action of a spring 24.

Body casting 8 and casting 12 are counter-bored to receive a compression spring 25 which surrounds the rod 21 and the lower end of which bears against the body portion 18 of the locator and the upper end of which bears against shoulders 26 of the counter-bore. The tendency of the spring 25 is to force the body portion 18 with its arms 18A and 18B downward when the latch 23 is released from engagement with the lug 22 on the rod 21, thus forcing the locator arms 18A and 18B out of the casting 12 and permitting movable locator arm 18B to swing into the open position shown in Fig. 13.

Latch 23 is released from engagement with lug 22 on the upstroke of the driver-locator unit by a fixed rod or bar 27 carried by the side frames of the machine. When the upper end of the latch 23 strikes the fixed bar 27 the spring 24 is depressed and the latch 23 is swung out of engagement with the lug 22 to the position shown in dotted lines in Fig. 16. When the latch 23 is released from engagement with the lug 22, compression spring 25 immediately moves the rod 21 carrying the body portion 18 and its arms 18A and 18B downward to the position shown in Fig. 13. This downward movement of the locator permits movable locator arm 18B to move into the open position shown in Fig. 13.

Driver 13 which is secured to casting 12 extends into the space between arms 18A and 18B. Said space extends up into the body portion 18 of the locator a sufficient distance so that the locator arms may be forced out of the casting 12 to the extent shown in Fig. 13 before further movement is arrested by the driver 13 which, as shown in Fig. 13, arrests downward movement of the locator when the movable arm 18B has assumed the position shown in Fig. 13.

The driver unit after contacting with the fixed cross bar 27 which releases the latch 23 from engagement with lug 22 moves downward for a locating and driving operation. As shown in Fig. 13 the prong P which is to be located and driven has been swung over onto the box part X by the bight-forming spindle 3.

The locator-driver unit continues to descend until fixed locator arm 18A contacts with the box part X, whereupon downward movement of the

arm 18A is arrested. Further downward movement of castings 8 and 12 force movable locator arm 18B from the open position shown in Fig. 13 to the closed position shown in Fig. 14. During this movement locator arm 18B engages the prong P and moves it over against fixed locator arm 18A directly beneath the driver 13 which continues to descend between locator arms 18A and 18B, driving the prong into the box part, as shown in Fig. 15.

During the driving movement the compression spring 25 has been compressed, as shown in Fig. 16, and the lug 22 on the top of rod 21 has been forced upwardly a sufficient distance within body casting 8 to permit the latch 23 to engage lug 22 and hold the rod 21 in its raised position. Thus, on the upstroke of the vertically reciprocating cross bar 7 the locator-driver unit is raised to stop position with locator arms 18A and 18B held within the casting 12.

The cycle of operation of the locator-driver unit is best shown in Figs. 17 to 22 inclusive. In Fig. 17 the machine is at rest and a box part X carrying its wire C has been placed on the supporting table in position to be operated upon by the machine of the application.

In Fig. 18 the machine has been started and the cross bar 7 has risen, causing the fixed cross bar 27 to depress the upper end of the latch 23 and release the latch from engagement with the lug 22, thereby permitting the compression spring 25 to force locator arms 18A and 18B out of casting 12 and permitting movable locator arm 18B to take the open position shown in Fig. 18.

In Fig. 19 the cross bar 7 has moved the locator-driver unit downwardly to the point where the fixed locator arm 18A has contacted with the box part X. As the locator arm 18A contacts with the box part X the bight-forming spindle 35 swings the prong P over the box part and toward fixed locator arm 18A, as shown.

In Fig. 20 continued downward movement of the cross bar 7 causes casting 12 to force movable locator arm 18B toward fixed locator arm 18A until said arms are in the position shown in Fig. 20. Movement of the locator arm 18B from the position shown in Fig. 19 to the position shown in Fig. 20 moves the prong P over against fixed locator arm 18A and holds the prong between the two locator arms directly beneath the driver 13 in position to be driven into the box part X by the driver 13.

In Fig. 21, the cross bar 7 has reached the lowermost point of its travel and has caused the driver to drive the prong through the box part X and to clinch the point of the prong on a clincher block or anvil 28. During this final drive movement the locator arms 18A and 18B are forced up into the casting 12 and the rod 21 carrying the locator 18 has been forced up into casting 8 far enough to permit the latch 23 to engage the lug 22 and hold the locator arms within casting 12 until released on the next upward movement of the bar 7.

The one cycle clutch disconnects when the locator-driver unit is in the position shown in Fig. 22, permitting the finished box part to be removed from the machine and another box part inserted for the next operation.

While only one locator-driver unit is illustrated and described herein, it will be understood that two such units are usually provided for each wire to be operated upon so that bights may be formed and perpetuated simultaneously on two wire-connected box parts.

The locator-driver unit of this invention is durable in construction, reliable in operation, and consists of but few operating parts.

It will be understood that the invention is not to be limited to the preferred embodiment shown for purposes of illustration.

It will also be understood that all of the inventive features need not be used conjointly but may be used in various combinations as defined in the subjoined claims.

I claim:

1. In a machine of the character described, a locator-driver unit comprising, in combination, a vertically reciprocating driver and a vertically reciprocating locator associated therewith, the locator having relatively movable locator arms, and the locator and the driver being movable relative to each other, a common actuator for the driver and locator, a separate yielding actuator for causing relative movement between the driver and the locator, and means to move one locator arm toward and from the other.

2. In a machine of the character described, a locator-driver unit comprising, in combination, a vertically reciprocating driver and a vertically reciprocating locator associated therewith, the locator having relatively movable locator arms, and the locator and the driver being movable relative to each other, a common actuator for the driver and locator, a separate actuator for causing relative movement between the driver and the locator, and means to move one locator arm toward and from the other.

3. In a machine of the character described, instrumentalities operable upon a wire secured to a box part to position the end of the wire and drive it into the box part, said instrumentalities including a locator-driver unit comprising, in combination, a driver and a locator associated therewith, the locator having relatively movable locator arms, and the locator and the driver being movable relative to each other, a common actuator for the driver and locator, a separate actuator for causing relative movement between the driver and the locator, and means to cause relative movement between the locator arms.

4. In a machine of the character described, instrumentalities operable upon a wire secured to a box part to position the end of the wire and drive it into the box part, said instrumentalities including a locator-driver unit comprising, in combination, a driver and a locator associated therewith, the locator having relatively movable locator arms, and the locator and the driver being movable relative to each other, a common actuator for the driver and locator, and a separate actuator for causing relative movement between the driver and the locator.

5. In a machine of the character described, instrumentalities operable upon a wire secured to a box part to position the end of the wire and drive it into the box part, said instrumentalities including a locator-driver unit comprising, in combination, a driver and a locator associated therewith, the locator having relatively movable locator arms, and the locator and the driver being movable relative to each other, and a common actuator for the driver and locator.

6. In a machine of the character described, instrumentalities operable upon a wire secured to a box part to position the end of the wire and drive it into the box part, said instrumentalities including a locator-driver unit comprising, in combination, a vertically reciprocating driver and a vertically reciprocating locator associated therewith.

- with, the locator having relatively movable locator arms, and the locator and the driver being movable relative to each other.
7. In a machine of the character described, instrumentalities operable upon a wire secured to a box part to position the end of the wire and drive it into the box part, said instrumentalities including a locator-driver unit comprising, in combination, a driver and a locator associated therewith, the locator having relatively movable locator arms, and the locator and the driver being relatively movable.
8. In a machine of the character described, instrumentalities operable upon a wire secured to a box part to position the end of the wire and drive it into the box part, said instrumentalities including a locator comprising, in combination, a pair of relatively movable arms and means to cause relative movement therebetween.
9. In a machine of the character described, instrumentalities operable upon a wire secured to a box part to position the end of the wire and drive it into the box part, said instrumentalities including a locator comprising, in combination, a pair of relatively movable arms and means to move one arm toward and from the other.
10. In a machine of the character described, instrumentalities operable upon a wire secured to a box part to position the end of the wire and drive it into the box part, said instrumentalities including a locator comprising, in combination, a pair of relatively movable arms and means to reciprocate said arms and to cause relative movement therebetween.
11. In a machine of the character described, instrumentalities operable upon a wire secured to a box part to position the end of the wire and drive it into the box part, said instrumentalities including a locator comprising, in combination, a pair of relatively movable arms and means to move said arms in a vertical plane and to cause relative movement therebetween.
12. In a machine of the character described, instrumentalities operable upon a wire secured to a box part to position the end of the wire and drive it into the box part, said instrumentalities including a locator comprising, in combination, a pair of relatively movable arms and means to move said arms in a vertical plane while causing relative movement therebetween.
13. In a machine of the character described, instrumentalities operable upon a wire secured to a box part to position the end of the wire and drive it into the box part, said instrumentalities including a driver and a locator, the driver and the locator being associated to reciprocate in the same direction.
14. In a machine of the character described, instrumentalities operable upon a wire secured to a box part to position the end of the wire and drive it into the box part, said instrumentalities including a driver and a locator, the driver and the locator being associated to reciprocate in the same direction and to move relatively to each other.
15. In a machine of the character described, instrumentalities operable upon a wire secured to a box part to position the end of the wire and drive it into the box part, said instrumentalities including a driver and a locator, the driver and the locator being relatively movable in the same direction.
16. In a machine of the character described, instrumentalities operable upon a wire secured to a box part to position the end of the wire and
- drive it into the box part, said instrumentalities including a driver and a locator, the driver and the locator being relatively movable vertically.
17. In a machine of the character described, instrumentalities operable upon a wire secured to a box part to position the end of the wire and drive it into the box part, said instrumentalities including a driver and a locator, the locator comprising a plurality of relatively movable arms and means to cause relative movement therebetween.
18. In a machine of the character described, instrumentalities operable upon a wire secured to a box part to position the end of the wire and drive it into the box part, said instrumentalities including a driver and a locator, the locator comprising a pair of relatively movable arms and means to move one arm toward and from the other.
19. In a machine of the character described, instrumentalities operable upon a wire secured to a box part to position the end of the wire and drive it into the box part, said instrumentalities including a driver and a locator, the locator comprising a pair of relatively movable arms and means to reciprocate said arms and to cause relative movement therebetween.
20. In a machine of the character described, instrumentalities operable upon a wire secured to a box part to position the end of the wire and drive it into the box part, said instrumentalities including a driver, a locator associated therewith, means to move the driver and locator in one direction, and means to cause relative movement between the driver and the locator.
21. In a machine of the character described, instrumentalities operable upon a wire secured to a box part to position the end of the wire and drive it into the box part, said instrumentalities including a driver and a locator associated therewith, the locator having a pair of relatively movable arms and the driver being movable between said arms.
22. In a machine of the character described, instrumentalities operable upon a flexible binder secured to a box part to position the end of the binder and drive it into the box part, said instrumentalities including a pair of arms mounted to permit one arm to move laterally toward and from the other arm, means to cause such movement, and means to move the arms in a vertical plane.
23. In a machine of the character described, instrumentalities operable upon a flexible binder secured to a box part to position the end of the binder and drive it into the box part, said instrumentalities including a pair of arms mounted to permit one arm to swing toward and from the other, means to cause such movement, and means to move the arms in a vertical plane.
24. In a machine of the character described, instrumentalities operable upon a flexible binder secured to a box part to position the end of the binder and drive it into the box part, said instrumentalities including a driver and a locator, the locator comprising a pair of arms mounted to permit one arm to move toward and from the other, and the driver being mounted to operate between the locator arms, means to cause one arm to move toward and from the other, and means to operate the driver.
25. In a machine of the character described, instrumentalities operable upon a flexible binder secured to a box part to position the end of the binder and drive it into the box part, said instru-

- mentalities including relatively movable arms to position the binder end for a driving operation and means to cause relative movement therebetween.
- 5 26. In a machine of the character described, instrumentalities operable upon a flexible binder secured to a box part to position the end of the binder and drive it into the box part, said instrumentalities including relatively movable arms to position the binder end for a driving operation and means to move one arm toward and from the other.
- 10

27. In a machine of the character described, instrumentalities operable upon a flexible binder secured to a box part to position the end of the binder and drive it into the box part, said instrumentalities including a pair of arms to position the binder end for a driving operation, one of said arms being mounted to swing toward and from the other, and means to cause such swinging movement.

ALFRED L. ROSEN MUND. 10
GEORGE P. IGLEHEART.
